(57) **CLAIM**

The ornamental design for a billiard ball image on an adhesive bandage, as shown and described.

DESCRIPTION

FIG. 1 is a perspective view of a billiard ball image on an adhesive bandage showing our new design;

FIG. 2 is a top plan view thereof;

FIG. 3 is a front elevational view thereof;

FIG. 4 is a bottom elevational view thereof;

FIG. 5 is a back elevational view thereof;

FIG. 6 is a left side elevational view thereof, the right side being a mirror image thereof;

FIG. 7 is a top plan view of an alternate embodiment thereof; and,

FIG. 8 is a top plan view of the billiard ball image on an adhesive bandage of FIGS. 1-6, shown in another environment.

The broken lines in the Figures are for illustrative purposes only and form no part of the claimed design.
